PAPER ROLL AND FEEDING AND CUTTING DEVICE

Samuel Nadelson, New York, N. Y.

Application April 4, 1933, Serial No. 664,310

16 Claims. (CL 45—68.3)

The present invention relates to improvements in medical and similar tables and it particularly relates to improvements in sanitary paper roller and feeding and cutting devices therefor.

5 Considerable difficulty has been experienced in providing a readily manipulated sanitary device which will provide temporary paper covers for medical and similar tables. It is quite laborious and unsatisfactory to use separate covers, each 10 of which are unfolded and placed upon the table. It is desirable to have a dispenser by which the doctor, physician or surgeon may conveniently and without difficulty immediately obtain a sheet 15 of paper to cover the table.

15 However, most of these dispensers are defective inasmuch as they are quite heavy and expensive and do not satisfactorily cooperate with the table. The paper rolls are not covered and collect dirt and dust and tend to loosen during usage of the 20 table and render manipulation of the table difficult. The paper which has been rolled to cover the table tends to pull or lengthen as well as ruffle. Moreover, frequently too much paper is 25 unrolled and considerable difficulty is encountered in removing the sheet after usage and is replacing it by a new sheet. In addition, the paper does not tend to stay on the table but rather tends to fall or slide away therefrom.

An object of the present invention is to provide 30 an improved medical or similar table construction in which, without increasing substantially the weight, expense or bulk of the table, it is possible to incorporate with the table a sanitary compact dispensing device by which the table may be conveniently and readily covered by a temporary 35 paper cover with the minimum of manipulation by the physician, doctor or surgeon using the same.

Other objects will appear during the course of 40 the following specification.

In accomplishing these objects it has been found satisfactory to provide a light sheet metal container, which will contain or embody suitable pivot mounts for the paper roll. The container is connected to one of the longitudinal ends of the 45 medical or surgical table in such a manner that it will be unobtrusively positioned below the upper surface thereof.

In one preferred form the enclosure may consist of a rectangular shaped box with a lid and be provided with a plurality of resilient pivot supports attached to the interior end walls thereof. These resilient pivot supports may serve to carry 50 a rod for sustaining the paper dispensing roll and at the same time may exert a springy action

against said paper roll to cause the paper to be in tension when the same is unrolled therefrom.

In the embodiment shown it has been found preferable to provide the container, enclosure or holder with a relatively heavy sheet metal flange 60 or angle member by which a connection may be made to the medical or similar table.

A cutting edge arrangement is provided upon the edge of the table so that the used paper cover may be conveniently torn away and removed. 65 This cutting edge arrangement may also be provided with means by which it will be possible for the physician or other user of the table to grasp most conveniently the torn sheet and to draw another cover for the table past the cutting edge. 70

The above and other objects will appear more clearly from the following detailed description, when taken in connection with the accompanying drawings which illustrate a preferred embodiment of the inventive idea. 75

In the drawings:

Fig. 1 is a perspective view showing the device of the present invention attached to a typical examining table or platform, as utilized by physicians. 80

Figs. 2 and 3 are side sectional views upon an enlarged scale upon the lines 2—2 or 3—3 of Fig. 4, Fig. 2 showing the paper roll and feeding device before final attachment to the table, and Fig. 3 showing it after final attachment to the 85 table.

Fig. 4 is a foreshortened longitudinal sectional view upon the line 4—4 of Fig. 2 of the paper roll and feeding device.

Fig. 4a is a perspective view of the pivot support element for the paper roll, before attachment. 90

Fig. 5 is a fragmentary front view upon an enlarged scale of the attachment of the paper roll and feeding device to the table, looking in the 95 direction of the arrow of line 5 of Fig. 2.

Fig. 5a is a fragmentary sectional view upon an enlarged scale of the attachment of the paper roll and feeding device to the table on the line 100 5a—5a of Figs. 3 and 4.

Fig. 6 is a fragmentary top view looking in the direction of the arrow of line 6 of Fig. 2, showing the tearing attachment.

Fig. 6a is a fragmentary perspective view illustrating the construction of the end of the tearing attachment. 105

Fig. 7 is a fragmentary top view of a modification similar to the arrangement shown in Fig. 6, and

Fig. 8 is a side sectional view of another em- 110

bodiment, particularly adapted to wooden medical tables.

In the drawings the medical table M of Fig. 1 is provided with a main table top section 10 having four symmetrically positioned legs 11 provided with suitable floor contact members 12. These legs 11 are also provided with longitudinal and transverse braces 13 and 14. To the front edge 15 of the table is pivotally connected the 10 folding leaf 16 which may be supported in elongation of the table 10 by a suitable brace (not shown). To the rear end of the table 17 may be connected the adjustable section 18, the position of which may be regulated by the parallel braces 15 19.

The braces 19, as shown, are provided with a series of spaced notches 20 which are received by the cross rod 21 transversely connected between two of the legs 11 of the table M so as to support the extension 18 at any desired angle to the table 10. To the rear end of the table of Fig. 1 is connected the paper roll and feeding device F of the present invention.

As shown in Figs. 2, 3 and 4 the sloping member 25 18 is of sheet metal construction having a sheet metal top 22 with side sheet metal flanges 23 and an end metal flange 24. The other table elements 10 and 16 are also of similar construction. The entire table M may be conveniently 30 coated with a sanitary appearing white enamel and if desired covered by a table pad.

The paper roll and feeding device F as shown in Figs. 2, 3 and 4, is provided with a casing or enclosure element C. An attachment A for connecting the paper roll and feeding device F to the table M and a tearing or cutting arrangement T.

The casing or enclosure C consists of a relatively thin sheet metal box which may for example be covered with white enamel or other suitable material. The box C has a top wall 30, a bottom wall 31, a rear wall 32 and side wall 33. As shown in Figs. 2, 3 and 4, the front end of the box is left open and is provided with a cover 34 having a hinge connection at 35 to the front edge of the bottom 31. The upper edge of the cover is beaded as indicated at 36 so as to give a smooth finish.

The side edges of the hinged cover 34 are provided with inwardly turned flanges 45 with the curved ends 48. These flanges are closely contacted with the sides 33 of the closure 34 and which are provided with cooperating snap tites 46 which are adapted to fit in and be received by the corresponding snap tites 47 on the side walls 33 (see particularly Fig. 5a).

To the side walls 33, are connected by spot welding or riveting the sheet metal pivot support members P (see particularly Figs. 2, 3, 4 and 60 4a) which are provided with two offset flat metal elements 37 and 38. The element 38 is connected to the end walls 33 of the enclosure C and the element 37 is provided with the locking or bayonet slot 39 to receive the ends of the pivot rod 40.

65 The pivot rod 40 passes through the roll of paper 41 which is centrally positioned within the casing C and the fingers or elements 37 of the pivots P are preferably resiliently bent inwardly toward each other so that they will closely contact with the sides of the wooden spools 42 inserted in the end of the roller and hold the paper under tension when it is being dispensed or fed.

To the inside of the ceiling 30 of the casing C is connected the attaching member A consisting 75 of channel bar 50 preferably of heavier sheet

metal than the casing C. The upper flange 51 of the channel bar 50 is resiliently pressed on the top of the inclined extension 18 of the table M, while the lower flange 52 is riveted or otherwise attached, as by screws, to the inside of the box or enclosure C, as indicated at 53.

The ceiling or top wall 30 of the box or enclosure 30 carries the thumb screws 54, 55 and 56, each of which is provided with a manual grip member 57. Although any number of these screws may be utilized with the type of table shown in Fig. 1 and as indicated in Figs. 2, 3 and 4, three screws are usually most satisfactory. The

side screws 54 and 56 are symmetrically positioned closely adjacent to the flange 23 and the corners between the flanges 23 and 24 and the central screw 55 is positioned substantially to the rear of the flange 24 and midway between the flanges 23.

The ceiling 30 being of relatively thin sheet metal is reinforced to receive the threaded shanks of the screws 54, 55 and 56, the flange 52 serving as sufficient reinforcement for the screws 54 and 56, and the attachment plate 58 being welded to the rear of the cover 30 to receive the rear screw element 55.

In order to obtain a most satisfactory rigid resilient connection of the enclosure C to the extension 18, the angle bar 50 is so arranged that it will be resiliently expanded upon attachment 105 of the casing or box C by the screws 54, 55 and 56.

It will be noted that the screws 54, 55 and 56 are screwed through the ceiling 30 of the box C until their rounded end portions at 60 contact with the lower bottom side of the sheet metal top 22 of the extension 18. The normal position of the flanges 51 and 52 of the channel member 50 are indicated in Fig. 2 and it will be noted that the two flanges 51 and 52 are bent toward each other.

When, however, the screws 54, 55 and 56 are tightened up the flange 52 will be forced downwardly to the position indicated in Fig. 3, and this separation of the flanges 52 and 53 will cause the top flange 51 to press against the top of the inclined extension 18 and assure a very rigid connection. It will be noted that the bending principally takes place between the flange 52 and the web of the channel 50. The angle of the flange 51 to the web is 90° so that the angle member will closely fit the edge of the table formed by the flange 24 depending vertically downwardly from the top surface 22.

The tearing arrangement is connected to the upper flange 51 of the attachment A, as shown particularly in Figs. 2, 3, 5, 6 and 6a.

The tearing bar 61 is inclined forwardly and downwardly as particularly indicated in Fig. 6a in the direction that the paper is drawn, as indicated by the arrows 90, but if desired it may also be positioned parallel to the flange 51.

As specifically indicated in Figs. 2, 4 and 6a the ends of the bar are clamped on spacer blocks or elements 62 by screws 63. These screws 63 extend downwardly through the ends of the tearing bar 61 and the spacer blocks 62 and into the body 140 of the flange 51.

In the arrangement as shown the rear opening 64 between the tearing bar 61 and the flange 51 is wider than the forward opening 65 so as to enable the ready insertion of the paper. The relatively narrow space or interval 65 between the front end or tearing bar 61 and the flange 51 enables more ready tearing or detachment of the sheet of paper to be removed. The inclination of the tearing bar 61 also assists in the tear-

ing action and renders the same more convenient.

As indicated in Fig. 6a the cutting bar is rounded at three corners 66 and is sharpened at its lower forward edge 67.

- 5 To prevent the paper from falling back in the box when it is being detached, a resilient clamp is provided consisting of one or more indentations 68 located symmetrically in the tearing bar 61. The depth of the indentation 68 of the tearing bar 61 is somewhat greater than the corresponding elevation of the spacer block 62, so that there will be a substantial tension exerted upon the sheet of paper passing under the tearing bar 61. As a result, when the used sheet of paper has been 15 detached by tearing along the bar 61 the strip of paper left between the carrying bar and the box C will be held by the indentation 68 and will be prevented from falling back into the casing or box C.
- 20 As shown particularly in Fig. 5 the corners of the channel member 50 are roughened at 70 preferably with a series of scorings or ridges which are transverse to the movement of the paper. As a result of this scoring or roughening, the paper 25 upon being drawn from the roll under tearing bar 61 will be subjected to substantial frictional effect, with the result that it will be statically charged opposite to the body of the table and to the top elements 18, 10 and 16 of such table.

- 30 The pivot elements P, and particularly the resilient slot containing elements 37 will press closely against the wooden spools 42 of the roll of paper 41, so that the paper upon being drawn under the tearing bar 61 will be subjected to considerable tension with resultant enhanced frictional contact at said edges 70.

- As indicated in Fig. 1, a tearing arrangement T² may be provided at the end of the leaf 16 in addition to and/or to take the place of the tearing arrangement T. In this case the sheet of paper instead of being grasped at the tearing strip T and drawn across the table elements 18, 10 and 16, will be grasped at the tearing arrangement T² and the used paper will be drawn under the tearing bar until the paper cover on top of the table has been changed. In this arrangement the friction engendered at the edges 70 of the channel 59 will cause the paper being drawn past the tearing bar 61 to be held closely thereto 50 by the static electric charge.

- After the used paper cover has been removed, the edge of the new sheet of paper is moved past the tearing strip 61 by upward pressure of the hand along the channel base 50. The edge of the paper, which is thus pushed past the tearing bar 61, may be grasped by the hand and drawn across the table to cover the surface thereof. For example, the paper may be drawn sufficiently to cover the inclined element 18 or to cover the 55 inclined element 18 and the horizontal element 10, or to cover the inclined element 18, the cover 10 and the rear leaf 16.

- It is often inconvenient, after the used paper sheet has been torn off at either the arrangement T or T², for the user of the table to slide the paper forwardly at the channel 50 of the tearing arrangement T in order that a new edge may be presented under the tearing bar 61 to be grasped.

- 70 In Figs. 2, 3, 4 and 6 is shown an arrangement which may be readily employed to obviate this difficulty. The arrangement has not been shown upon Fig. 1 in view of the small scale of the elements of this Figure. According to this arrangement the sheet of paper instead of being torn along the front straight edge of the tearing

bar 61 will be torn along a tab or projecting element on the front of the tearing strip. In this manner, a forwardly projecting tab or ear on the paper edge will be formed which may be most readily grasped by the hand.

In Figs. 2, 3, 4 and 6, the tab plate 80 is pivotally connected at 81 to the tearing bar 61, the spring 82 being provided to move the tab plate downwardly, at all times, and hold it in position in contact with the front edge of the flange 51 as indicated in Figs. 2 and 3.

When the paper is torn along the front edge of the bar 61, it will tear around the edge 83 of the tearing tab 80. Thereupon the user of the tab may readily lift up the tab plate 80, grasp the tab or paper therebelow and readily draw the new sheet through the tearing arrangement T.

In Fig. 7 is shown a slight modification of this arrangement in which the tab plate 84 is provided with slots 85 which receive pins 86 on the tearing bar 61. Between the pins 86 attached to the tearing bar 61 and pins 87 attached to the tab plate 84 are the springs 88 which bias the tab plate 84 forwardly.

When the used sheet of paper is removed and torn along the front edge of the tearing bar 61 and the tab plate 84, the tab plate 84 may be pushed rearwardly and the tab of paper therebelow grasped by the physician or person using the table. The new sheet of paper may then be readily drawn therethrough.

The arrows 90 on Figs. 1, 2, 3, 5, 6, 6a and 7 indicate the movement of the sheet of paper, the sheet of paper being diagrammatically illustrated 110 at L in Figs. 1, 2 and 3. Upon being unwound from the roll 41 as shown in Figs. 2 and 3 the paper may either be caused to pass from the top of the roll adjacent the ceiling 30 as indicated by the arrows 91 or from the front side of the roll 115 adjacent from the roll as indicated by the arrows 92. In the former instance care must be taken that the paper is not torn by the thumb screws 57.

The arrangement shown in Figs. 1, 2 and 7 is particularly adapted to modern metallic or surgical examining tables of sheet metal construction. Since there are, however, a great many wooden medical and surgical examining tables still being used, the invention of the present application may be associated therewith without 125 any substantial change therein and such association is shown in Fig. 8.

In Fig. 8 the box or container C may be of substantially the same construction as shown in Figs. 2 and 3 except that the ceiling 30 will contact with the edge 100 of the wooden table, part of which is indicated at 101. The cover 34 will open upwardly and the pivot element P will be displaced as indicated.

In the construction of Fig. 8 the channel member 50 is replaced by a right-angle bar element 105. One flange of this bar is provided with openings to enable attachment thereof to the top edge of the table 101 by the wood screws 106, while the other flange thereof is provided with 140 similar openings to enable the clamping thereof to the table 101 by the wood screws 107.

It will be noted that the paper roll and its pivot supports in the enclosure are protected from dirt and dust. The casing C shown in Figs. 145 2, 3 or 8 is placed under the table 18 where it will not be obtrusive or be readily apparent.

The clamping thumb screws 54, 55 and 56 assure a particularly rigid connection which adapts the device F of the present invention to be fitted 150

to a large number of different sizes and shapes of tables and assure that the device will not loosen during inclination or movement of the inclined table element 18.

5 Even though the physician or surgeon using the table be quite careless in drawing the new paper cover through the tearing device, the static engendered will assure that the paper will cling closely to the table and not fall therefrom. Moreover, the tab plates 80 and 84 will enable convenient grasping of the new paper cover after the old paper cover has been ripped off. The tensioning projection 68 will prevent the paper from falling into the box after the tearing operation.

10 15 The attachment A, in addition to being utilized for attaching the device F to the table, may also be employed for grasping the end of a pad laid upon the table. The box or casing C is shown as made of rectangular form, but if desired it may 20 be made of cylindrical or semicylindrical shape. The channel bar 50 of the attachment A is preferably of relatively heavy bright unenamelled steel, while the rest of the box C is of relatively thin enamelled stock.

25 Although my invention is not restricted to any dimensional limitations, it may be of value to illustrate this invention by the dimensions of one specific embodiment. For a commercial utilization, it has been found particularly satisfactory to 30 make the device F of the present invention of substantially the following dimensional size: The height of the casing C in this commercial embodiment is 6", its width is 5" and its length is about 20". The spacing of the channel bar 35 flanges 55 and 52 may be varied between 1 1/4" and 2". The width of the flanges may conveniently be about 1 1/2". The metal in the channel 40 45 bar 50 may vary between 1/8" and 1/16" in thickness while the sheet metal in the box C may be about 1/64" in thickness. The forward thumb screws 54 and 56 may be separated from each other by a space of about 17". The tearing bar 61 may be made 1/2" in width and of about 1/8" in thickness.

45 What is claimed is:

1. In combination with a medical or surgical table, a sanitary paper roll and feeding and cutting device having a detachable connection thereto and consisting of a boxlike enclosure with a 50 hinged cover and with pivot support to receive a paper roll, an attachment element supporting said enclosure upon the edge of said table and a tearing element on said attachment and connected to said attachment.

55 2. The combination with a medical or surgical table, a sanitary paper roll and feeding and cutting device, said device including a paper roll, a box enclosure therefor, an attachment supporting said enclosure upon the edge of said 60 table, a tearing element on said attachment, said box being provided with pivot support elements attached to the sides thereof and exerting tension on the sides of the roll when it is turned and a roughened surface on said attachment over 65 which the sheet of paper is drawn to cause static electric charge to be engendered thereon.

3. In a medical or surgical table of the type having a central elevated table element with a plurality of spaced supporting legs, and a plurality of adjustable swinging end sections with 70 adjustable support means for each of said sections, the combination therewith of a sanitary paper roll and feed device located underneath the table including a casing of sheet metal, an attachment including an angle member, said at-

80 tachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means.

85 4. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, and an attachment including an angle member, said attachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means, 90 said casing consisting of a rectangular box, one of the walls of which has a hinged connection whereby it will serve as a swinging closure, said hinged wall being provided with side flanges with snap fits whereby it is locked in position.

95 5. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including an angle member, said attachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means, said casing 100 consisting of a rectangular box, one of the walls of which has a hinged connection whereby it will serve as a swinging closure, 105 the interior end walls of said box being provided with offset sheet metal pivot members with bayonet slots receiving the pivot rod for a paper roll, the offset portions 110 resiliently contacting with the ends of the paper roll to maintain the paper sheet under tension when being unrolled.

115 6. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including a channel bar, said attachment firmly connecting said device to one of the ends of one of said adjustable end sections so that it will be located unobtrusively below the upper surface 120 thereof, one of the legs of said channel bar being positioned on the top of said adjustable end section, said attachment being provided on its upper surface with a tearing means, the web of said channel bar contacting the end of said section, 125 and the other leg of said channel bar projecting inside of said casing and being firmly attached to the ceiling of said casing.

130 7. In a medical or surgical table of the type having a central elevated table element with a

- plurality of spaced supporting legs, and a plurality of adjustable swinging end sections with adjustable support means for each of said sections, the combination therewith of a sanitary paper roll and feeding and cutting device including a casing of sheet metal, an attachment including a channel bar, said attachment firmly connecting said device to one of the ends of one of said adjustable end sections so that it will be located unobtrusively below the upper surface thereof, one of the legs of said channel bar being positioned on the top of said adjustable end section, said attachment being provided on its upper surface with a tearing means, said channel bar being provided with roughened angle edges over which the paper is to be drawn, the friction causing a static electrical charge to be engendered whereby said paper will closely cling to said table element and to said swinging end sections. 8. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including a channel bar, said attachment firmly connecting said device to one of the ends of one of said adjustable end sections so that it will be located unobtrusively below the upper surface thereof, one of the legs of said channel bar being positioned on the top of said adjustable end section, said attachment being provided on its upper surface with a tearing means, said end section being of sheet metal construction with downwardly depending end and side flanges, and the ceiling of said casing being provided with a plurality of thumb screws clamping the channel bar against the end of the table. 9. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including a channel bar, said attachment firmly connecting said device to one of the ends of one of said adjustable end sections so that it will be located unobtrusively below the upper surface thereof, one of the legs of said channel bar being positioned on the top of said adjustable end section, said attachment being provided on its upper surface with a tearing attachment, the web of said channel bar being vertical and being clamped against the end of said adjustable section, the other leg of said channel bar extending inside of the container, and said container being provided with a plurality of thumb screws whereby the legs of said channel may be separated to tension the bar against the end of said adjustable section. 10. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including an angle member, said attachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means, said tearing means consisting in part of a metal strip slightly spaced above the top of said side of the angle member and being inclined downwardly and forwardly in the direction of the movement of the paper sheet. 11. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including an angle member, said attachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means, said tearing attachment consisting of a flat metal strip extending transversely across the top of said adjustable section and being inclined forwardly and downwardly and being provided with downwardly extending projections contacting with the paper being drawn therebelow whereby said paper will be held from falling back into the container when the used sheet is torn along the tearing means. 12. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including an angle member, said attachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means, said tearing means being provided with a tab plate whereby upon tearing of the used sheet of paper along said tearing device a tab will be left by which a new sheet of paper may be readily grasped and drawn under the tearing means from the sheet metal container. 13. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including an angle member, said attachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means, said tearing means being provided with a pivotally connected tab plate provided with a coil spring to press it downwardly, whereby upon tearing of the sheet of paper along the tearing means a tab of paper will be left which may be 140

readily grasped upon lifting the tab plate, enabling drawing through of a new sheet of paper.

14. In a medical or surgical table of the type having a central elevated table element with a plurality of spaced supporting legs, and a plurality of adjustable swinging end sections with adjustable support means for each of said sections, the combination therewith of a sanitary paper roll and feeding and cutting device including a casing of sheet metal, an attachment including an angle member, said attachment firmly connecting said device to one of the ends of one of said adjustable end sections so that it will be located unobtrusively below the upper surface thereof, one of the sides of said angle member being positioned on the top of said adjustable end section, said attachment being provided on its upper surface with a tearing means, said tearing means being provided with a sliding tab plate having a plurality of longitudinal slots, said top side of said angle member being provided with pins fitting into said slots and resilient means to push the tab plate forwardly, said resilient means permitting the tab plate to be pushed rearwardly whereby the tab left after the tearing operation may be grasped, enabling drawing through of a new sheet of paper.
15. In a medical or surgical table of the type having a central elevated table element with a plurality of spaced supporting legs, the combination therewith of a sanitary paper roll and feeding and cutting device including a casing of sheet metal, an attachment including hooking means firmly connecting said device to the end of said element so that it will be located unob-

trusively below the upper surface thereof, said attachment being provided on its upper surface with a tearing member, said attachment including a flat metal strip extending transversely across said table element and being provided with downwardly extending projection means contacting with the paper being drawn therebelow whereby said paper will be held from falling back into the container when the used sheet is torn along the tearing member, said attachment also including thumb screws projecting upwardly through and having a threaded connection in the ceiling of said casing, whereby said hooking means may be tensioned on said end of said table element.

16. In a medical or surgical table of the type having a table element with a plurality of spaced supporting legs, the combination therewith of a sanitary paper roll and feeding and cutting device including a casing of sheet metal, an attachment including a hooking member firmly connecting said device to one of the ends of said element so that it will be located unobtrusively below the upper surface thereof, said attachment being provided with a tearing means, with a paper holding means and with tab forming means, said tearing means enabling ready severance of the used paper sheet, said tab forming means assuring the formation of a tab by which it is possible to pull another sheet of paper from the paper roll in the casing onto the top of the table element, and said paper holding means holding said tab in position and preventing it from falling back into said casing.
